US00D742932S

(12) **United States Design Patent**
Ewingmann

(10) **Patent No.:** **US D742,932 S**
(45) **Date of Patent:** **** Nov. 10, 2015**

(54) **ROAD CONSTRUCTION MACHINE**

(75) Inventor: **Ulrich Ewingmann**,
Taufkirchen-Potzham (DE)

(73) Assignee: **JOSEPH VOGEL AG**,
Ludwigshafen/Rhein (DE)

(**) Term: **14 Years**

(21) Appl. No.: **29/412,335**

(22) Filed: **Feb. 1, 2012**

(30) **Foreign Application Priority Data**

Aug. 1, 2011 (EP) 001289920

(51) **LOC (10) Cl.** **15-03**

(52) **U.S. Cl.** **D15/22**
USPC **D15/22**

(58) **Field of Classification Search**
USPC D15/10, 13, 19, 22-26; 404/75, 108,
404/101, 102, 110, 118, 87.05

(57) **CLAIM**

The ornamental design for a road construction machine, as shown and described.

DESCRIPTION

FIG. 1 is a left side view of a road construction machine showing my new design.

FIG. 2 is a front view thereof.

FIG. 3 is a right side view thereof.

FIG. 4 is a rear view thereof.

FIG. 5 is a top plan view thereof.

FIG. 6 is a bottom plan view thereof.

FIG. 7 is a front, left, top, perspective view thereof.

FIG. 8 is a further rear, right, top perspective view thereof.

FIG. 9 is a left side view of a second embodiment of a road construction machine showing my new design.

FIG. 10 is a front view thereof.

FIG. 11 is a right side view thereof.

FIG. 12 is a rear view thereof.

FIG. 13 is a top plan view thereof.

FIG. 14 is a bottom plan view thereof.

FIG. 15 is a front, left, top, perspective view thereof.

FIG. 16 is a further rear, right, top perspective view thereof.

FIG. 17 is a front view of a third embodiment of a road construction machine showing my new design.

FIG. 18 is a right side view thereof.

FIG. 19 is a rear view thereof.

FIG. 20 is a top plan view thereof.

FIG. 21 is a bottom plan view thereof.

FIG. 22 is a front, left, top, perspective view thereof; and,

FIG. 23 is a further rear, right, top perspective view thereof.
